(57) **CLAIM**

The ornamental design for a face shield with head strap assembly, as shown and described.

DESCRIPTION

FIG. 1 is a front perspective view of a face shield with head strap assembly showing our new design;

FIG. 2 is another front perspective view thereof;

FIG. 3 is a front view thereof;

FIG. 4 is a left side view thereof;

FIG. 5 is a right side view thereof;

FIG. 6 is a rear view thereof;

FIG. 7 is a top view thereof;

FIG. 8 is a bottom view thereof;

FIG. 9 is a rear perspective view thereof, in a flattened storage position;

FIG. 10 is a front perspective view of a second embodiment thereof;

FIG. 11 is another front perspective view of FIG. 10;

FIG. 12 is a front view of FIG. 10;

FIG. 13 is a left side view of FIG. 10;

FIG. 14 is a right side view of FIG. 10;

FIG. 15 is a rear view of FIG. 10;

FIG. 16 is a top view of FIG. 10;

FIG. 17 is a bottom view of FIG. 10; and,

FIG. 18 is a rear perspective view of FIG. 10, in a flattened storage position.

The details shown in broken lines form no part of the claimed design.
